UNITED STATES PATENT OFFICE.

SIMON DEUTSCH, OF DETROIT, MICHIGAN.

IGNITION SYSTEM.

1,205,167.

Specification of Letters Patent. Patented Nov. 21, 1916.

Application filed March 29, 1916. Serial No. 87,391.

To all whom it may concern:

Be it known that I, SIMON DEUTSCH, a citizen of the United States, and residing at Detroit, in the county of Wayne and State of Michigan, have invented a new and Improved Ignition System, of which the following is a specification.

This invention relates to means for igniting the explosive gases in the cylinders of multi-cylinder internal-combustion engines, and its object is to provide an improved system whereby a single induction coil or other high tension source may be utilized for the ignition of the gases in a series of cylinders by having the current therefrom electro-magnetically distributed to said cylinders.

This invention consists in a source of high tension current, preferably an induction coil, the primary winding of which may be connected to a plurality of sources of low tension current, of a series of spark-plugs, a separate circuit between each spark-plug and the secondary winding of the induction coil, an electro-magnetic switch in each said circuit, a current distributor operated by an engine, a circuit connecting the winding of each electro-magnetic switch to the primary winding of said induction coil and to said distributor, which circuits are closed in sequence by said distributor as a current is desired at the spark-plugs to explode the charges in the cylinders of the engine.

This invention further consists in adjusting means for said distributor whereby the occurrence of the sparks at the spark-plugs may be advanced or retarded.

In the accompanying drawing, Figure 1 is a diagrammatic view of the invention. Fig. 2 is a view of one of the electro-magnetic switches.

Similar reference characters refer to like parts in both views.

The current distributor, commonly known as the "timer", shown conventionally, consists of a disk 1 in which insulated contacts 2 are mounted, each adapted to be engaged by the arm 3 secured to the shaft 4 which is driven by the engine. The arm 3 and shaft 4 may be grounded by the wire 5. Wires 6, 7, 8 and 9 connect to the various contacts 2 and to the windings of the magnets 16, 17, 18 and 19, respectively. The opposite ends of the windings of these magnets connect to the bus-bar 15 by wires 14. Each core 20 of these electro-magnets, when

a current passes to its winding, draws up an armature 26, 27, 28 or 29, which is connected to the bus-bar 21 by means of a wire 36, 37, 38 or 39, and when the armature is drawn up against the core, a high tension current will pass from the bus-bar 21 to one of the spark plugs 46, 47, 48 or 49 (of which there is one for each cylinder of the engine), over the wire 56, 57, 58 or 59, according as the arm 3 engages with the contact 2 at the end of the wire 6, 7, 8 or 9. The spark-plugs may all be of any well known construction and their cylinders are grounded, this fact being indicated by the wires 23, although the engine itself constitutes the "ground". The primary winding 30 of the induction coil connects to the vibrator 31 and to the switch arm 32. A storage battery 33 connects to the contact 34 and is grounded by the wire 35. A magneto 40 connects to the contact 41 of this switch and is grounded by the wire 42. The magneto will preferably be driven by the engine and produce an alternating current. The contact point 43 of the vibrator connects to the bus-bar 15 by means of the wire 44.

The secondary winding 50 of the induction coil connects to the bus-bar 21 by means of a wire 51 and to the wire 44 by means of a wire 52. While four spark-plugs are shown, it will be understood that this number may be varied as desired.

As the arm 3 engages the contact 2 at the end of the wire 6, a current will flow from the magneto 40 over the primary winding of the induction coil to the bus-bar 15, over the wire 14, the winding of the magnet 16, causing its core to draw up the armature 26, then over the wire 6, the arm 3 and wire 5 to ground. The secondary current will be from the wire 44, over wire 52, the secondary winding 50 and wire 51 to the bus-bar 21, thence over the wire 36, switch 26 and wire 56 to the spark-plug 46.

Each spark-plug thus receives a current during such time as the arm 3 engages the contact 2 at the end of the main wire of the primary lead 6, 7, 8 or 9 of that particular spark-plug, and this current stops as soon as this engagement is broken, even if the magnet should be slow in releasing its armature, which slowness may be desirable on account of the interruption in the primary circuit by the action of the vibrator 31. As only one induction coil is employed,

absolute synchronism is assured, which is impossible where a separate induction coil is used for each spark-plug.

By mounting the pivot 60 of the armature 65 on a metal frame 61 quite near the core 20 of the magnet, as indicated in Fig. 2, a large movement of the contact 62 of the armature is obtained. It may be desirable to so mount the stationary contact 63 that 10 a gap 64 results, which gap will serve to intensify the spark, acting somewhat as a condenser. With these magnets all mounted in a case having proper transparent openings, the sparks will be visible and detection of the reasons for improper firing will be facilitated.

The distributor or timer 1 is preferably rotatable to advance or retard the ignition sparks in the usual manner, this being indicated by the arm 66 and the arrows leading therefrom. Details of construction are omitted for the reason that all the elements employed are well-known, the novelty residing entirely in the combination or assembling of these elements.

I claim:—

1. In an ignition system for internal combustion engines, the combination of an induction coil, of a series of spark plugs, a separate circuit between each spark plug and the secondary winding of the induction coil, an electro-magnetic switch in each said circuit, one end of the winding of each switch connecting to one end of the primary winding of the induction coil, a current distributor comprising a series of contacts, one for each magnet winding, and a revolving arm adapted to ground each contact in turn, a separate wire to connect each contact to its magnet winding, and a current source connected to the opposite end of the primary winding.

2. In an ignition system for internal combustion engines, the combination of an induction coil and bus-bars connected to the primary and secondary windings thereof, a series of spark plugs, a separate circuit to connect each spark plug to the secondary current bus-bar, a normally open magnetic switch in each said circuit, a current distributor, and circuits to the windings of said magnetic switches adapted to be closed by said distributor.

3. In an ignition system for internal combustion engines, the combination of an induction coil, a series of spark plugs, a separate circuit connecting each spark plug to the secondary current winding of the induction coil, a normally open electro-magnetic switch in each said circuit, a normally open circuit connecting to the pole winding of each magnetic switch and to the primary winding of said induction coil, and means operated by the engine for intermittently closing said last named circuits in sequence

and thereby causing the closing of the switches and the passage of current to the spark plugs.

4. In an ignition system for internal combustion engines, the combination of a primary winding of an induction coil, means to energize the same, a secondary winding for said coil, a series of electro-magnetic switches, ignition devices for said engine, circuits leading from the secondary winding 75 to said ignition devices and respectively controlled by said switches, and means for controlling the passage of current over each of said circuits in turn.

5. In an ignition system for internal combustion engines, the combination of a current distributor operatively connected to the engine and contacting in a predetermined sequence, spark-plugs for the cylinders of the engine, an induction coil, electro-magnetic switch windings in series with the primary winding of the induction coil and with the contacts of said distributor and in parallel with each other, and switch contacts operated by said magnetic switch windings 90 when energized for conducting the induced high tension current to the spark-plugs.

6. In an ignition system for internal combustion engines, the combination of a current distributor operatively connected to the engine and contacting in a predetermined sequence, spark-plugs for the cylinders of the engine, an induction coil, electro-magnetic switch windings in series with the primary winding of the induction coil and with the contacts of said distributor and in parallel with each other, switch contacts operated by said magnetic switch windings when energized for conducting the induced high tension current to the spark-plugs, and means to prevent said switch contacts from completely engaging so as to produce an auxiliary spark gap.

7. In an ignition system for internal combustion engines, the combination of a low tension current distributor operatively connected to the engine and capable of adjustment to advance or retard the ignition spark and contacting in a predetermined sequence, spark-plugs, an electro-magnet for each spark-plug, the windings of said electro-magnets being connected to said distributor, and means operated by each electro-magnet when selected by said distributor for connecting a high tension current to its spark-plugs.

8. In an ignition system for internal combustion engines, the combination of a rotary current distributor, spark-plugs, an electro-magnet for each spark-plug, a circuit connecting the windings of each electro-magnet to said distributor, and means operable by each electro-magnet for connecting a high tension current to its spark-plug including 130

- a pair of terminals constituting a spark-gap to intensify said high-tension current.
9. In an ignition system for multi-cylinder internal combustion engines, the combination of the primary and secondary windings of an induction coil, means to energize the same, a series of spark-plugs, an electro-magnetic switch for each spark-plug, a normally open circuit between each spark-plug and said secondary winding adapted to be closed by its electro-magnetic switch, circuits connecting said primary winding to the windings of said switches, and means for causing the passage of current over each said last named circuits in turn.
10. In an ignition system for internal combustion engines, the combination of an induction coil and conductors connected to the primary and secondary windings thereof, a plurality of spark plugs, a separate circuit to connect each spark plug to the secondary current conductor, an electro-magnetic switch controlling each said circuit, a current distributor, and circuits to the windings of said magnetic switches adapted to be controlled by said distributor.
11. In an ignition system for internal combustion engines, the combination of an induction coil, a series of spark plugs, a separate circuit connecting each spark plug to the secondary current winding of the induction coil, an electro-magnetic switch in each said circuit, a circuit to the winding of each magnetic switch, and means operated by the engines for intermittently closing said last named circuits in sequence and thereby causing the operation of the switches and the passage of the current to the spark-plugs.
12. In an ignition system for internal combustion engines, the combination of a low tension current source, electro-magnetic switches, circuits for connecting the low tension current source to the windings of said switches, a high tension current source, a series of spark-plugs, a separate circuit connecting each spark-plug to said high tension current source, and means for controlling the passage of current over each of said circuits.
13. In an ignition system for internal combustion engines, the combination of a low tension current source, electro-magnetic switches, circuits for connecting said low tension current source to the winding of said switches, a high tension current source, spark-plugs, a separate circuit connecting each spark-plug to the high tension current source and controlled by said magnetic switches, and means operated by the engine for controlling the first named circuits, and thereby causing the operation of the switches and controlling the passage of said high tension current to the spark-plugs.
14. In an ignition system for internal combustion engines, the combination of a low tension current source, a high tension current source, spark plugs, an electro-magnet for each spark-plug, means operatively connected to the engine and capable of adjustment, for connecting the windings of said electro-magnets to said low tension current source, and means operated by each electro-magnet for connecting said high tension current source to its spark-plug.
15. In an ignition system for internal combustion engines, the combination of a low tension current source, a low tension current distributor operatively connected to the engine and capable of adjustment to advance or retard the ignition spark and contacting in a predetermined sequence, a high tension current source, spark-plugs, an electro-magnet for each spark-plug, the winding of each electro-magnet being connected to said distributor and means operated by each electro-magnet when selected by said distributor for connecting said high tension current source to its spark-plug.
16. In an ignition system for internal combustion engines, the combination of a low tension current source, a high tension current source, spark-plugs, an electro-magnet for each spark-plug, means operatively connected to the engine and capable of adjustment for connecting the windings of said electro-magnets to said low tension current source, and means operated by each electro-magnet for connecting said high tension current source to its spark-plug, said means including a pair of terminals constituting a spark-gap.
17. In an ignition system for multi-cylinder internal combustion engines, the combination of a primary and secondary winding of an induction coil, means to energize same, a series of spark-plugs, an electro-magnetic switch for each spark-plug, a circuit between each spark-plug and said secondary winding adapted to be controlled by its electro-magnetic switch, circuits connecting the windings of said switches with said energizing means, and means for causing the passage of current over each said last named circuits in a predetermined sequence.

SIMON DEUTSCH.
